UNITED STATES PATENT OFFICE

EDWIN W. TILTON, OF HAVERHILL, MASSACHUSETTS, ASSIGNOR TO LEWIS L. COWAN,
OF CINCINNATI, OHIO

CUTTING, SORTING, AND CONVEYING DEVICE

Application filed July 25, 1933. Serial No. 470,644.

The invention relates to means adapted to cut, sort and convey shoe soles.

Heretofore, considerable loss of time has been occasioned the operators of shoe sole cutting machines in collecting, sorting and packing the rights and lefts soles in boxes for shipment or storage. It has been customary for the operators of machines of this kind to manually collect and sort the right and left cut soles from and around the machine, after which the soles are packed in boxes or containers for shipment.

The objects of the invention are to provide simple, efficient, economical, and durable means whereby rights and lefts shoe soles are adapted to be automatically sorted and conveyed from the cutting machine to packing boxes; and to provide means whereby the scrap material, or cat-tails, are automatically separated from the cut soles.

The invention consists in the combination of the elements, arrangement of the parts and in the details of the construction, as hereinafter claimed.

In the drawings:

Fig. 1 is a vertical transverse section of the invention;

Fig. 2 is a section taken on a line corresponding to 2—2 in Fig. 1;

Fig. 3 is a plan view of the invention;

Fig. 4 is a side elevational view of the invention;

Fig. 5 is a plan view of the invention, with parts removed;

Fig. 6 is a side elevational view of the invention.

The preferred construction of the invention, hereinafter described may be utilized in combination with any presently used shoe sole cutting machine of well known construction. In the drawings is shown one form of a usual shoe sole cutting machine 1 comprising the table 2 upon the horizontal apron or top 2' on which a strip of leather is placed previous to its being cut by the knives 3 and 4, respectively, to form the right and left shoe soles.

The knives 3 and 4, respectively, are fixed to the upper ends of the curved supports 5 and 6 having their lower ends 7 and 8 rotat-

ably connected with the lugs 9 and 9' mounted in the upper edges of the sides 10 and 11 of the table 2.

Intermediate the front end 12 and the rear end 13 of the table, and secured to the rear edge 16 of the apron 2', is the block 17 formed of wood, or other suitable material, received in the rectangular support 18 having its upper edge 19 suitably secured to the lower surface 20 of the top 2'. The block 17 may have a groove, in its upper surface, into which the cutting edges 22 and 23 and the knives 3 and 4 may be received, or when adjusted at a higher elevation the knives contact the block without entering grooves.

Suitably journaled in the vertical sides 10 and 11, of the table 2, is a horizontal shaft 24, which extends transversely of the table and has fixed to its end 25 the pulley 26 adapted to be rotated by suitable outside source of supply. Adjacent the pulley 26 is the usual clutch 27 receivable on the shaft 24 whereby the shaft 24 is adapted to be rotated or its movements stopped when the pulley 26 rotates continuously.

Beneath the shaft 24 are the spaced apart horizontal shafts 28 and 29 having their outer ends suitably journaled in the sides 10 and 11 of the table 2. Suitably fixed to the shaft 24 is the pinion gear 30 which meshes with the gear 31 suitably fixed to the shaft 28. Adjacent the gear 31 is the gear 32, fixed to the shaft 28 meshing with the gear 33 suitably fixed to the shaft 29. On the outer protruding ends 34 of the shafts 28 and 29 are the cranks 35 having fixed thereto the upwardly extending connecting rods 36 having their upper ends 37 rotatably connected with the lugs 38 extending horizontally and outwardly from the upper ends of the arms 5 and 6 whereby rotatable movement of the shaft 24 is adapted to cause the knives 3 and 4 to move alternatively from the position shown in Fig. 6 downwardly with their cutting edges 22 and 23 receivable on the block 17. The cranks 35, on the shaft 28 are advanced, with respect to the cranks 35 on the shaft 29 whereby the cutting edge 22 of the knife 3 is adapted to contact the block 17, adjacent the grooves 21, and recede there-

from a short period of time before the cutting edge 23 of the knife 4 contacts the block.

Rotatably mounted in the upper edges of the sides 10 and 11, of the table, is the horizontal shaft 39 having suitably fixed thereto the spaced apart receiving wheels 40 and 41 each comprising a plurality of equal distance spaced apart plates 42 having their inner edges suitably fixed to the hub 43 which is fixed to the shaft 39. The wheels 40 and 41 are arranged adjacent the block 17 and are positioned so that the space 44, between the outer edges of the plates 42 and the rear side of the block 17, permits the scrap material, or cat-tails, to drop on the floor, or in a receptacle which may be suitably fixed to the sides of the table.

Fixed to the outer end 45 of the shaft 39 is the ratchet connection 46 with the upper end 47 of the connecting rod 48 having its lower end connected with the crank 49 fixed to the outer protruding end 50 of the shaft 24 whereby, during operation of the machine, the wheels 40 and 41 intermittently rotate and remain stationary.

When the operator positions the leather strip properly on the top 2' of the table 2, during the period when the knives 3 and 4 are in the upward position shown in Fig. 6, the wheels 40 and 41 remain stationary. Downward movement of the arms 5 and 6 cause the cutting edges 22 and 23 of the knives 3 and 4 to alternatively cut a right and a left sole from the leather strip, since the cutting edges of the knives are properly formed to accomplish this result. After the knives have cut the soles from the strip and have begun their upward movement, and the wheels 40 and 41 are in stationary position the operator slides or moves the leather strip toward the rear of the table whereby the soles are moved between the plates 42 on the wheels. The scrap material falls between the outer edge 44 of the plate and the block 17. Further movement of the arms 5 and 6, through operation of the mechanism previously described causes the wheels 40 and 41 to rotate in the direction indicated by the arrow 51 whereby successive movements of the knives, and the operator forcing the leather strip toward the rear of the table, causes the soles, forced between the plates 42, to drop from the wheel into the respective inclined chutes 52 and 53 fixed to the upper ends of the rods 54 and 55 having their lower ends connected with the pins 56 and 57 and the links 56' and 57' connected with the lower ends of the connecting rods 36 and 37 whereby the movement of the chutes is regulated to cause the right hand soles to fall into chute 52 and the left hand soles to fall into chute 53 from the wheels 40 and 41. The soles slide downwardly of the chutes and fall therefrom into suitable receptacles placed thereunder. The rocking action of the connecting rods 54 and 55 are timed to cause

the chutes to move toward and away from the wheels 40 and 41 so that the chute 52 is positioned to catch the right sole when it drops and the chute 53 is properly positioned to catch the left sole when it drops.

An advantage of the invention is that the soles, as cut from the leather strip, are automatically conveyed from the machine 1 into the packing or shipping boxes 52' and 53' which are positioned beneath the chutes or troughs 52 and 53, without the necessity of being touched or handled by human agency, whereby the the labor cost usually associated with cutting and packing shoe soles is importantly reduced.

It is therefore apparent that I have invented a highly desirable device of the character described which may be utilized with various kinds of shoe sole cutting machines by modification of the means by which the wheels 40 and 41 are operated in accordance with the particular construction of the machines with which the invention is utilized.

My device may be made of any size, and constructed of any materials deemed convenient and suitable for a device of this character, and while I have illustrated and described a form of construction and arrangement of parts found desirable in materializing the invention, I wish to emphasize the fact that I desire to include in this application all mechanical equivalents and substitutes that may fairly be considered to come within the scope and purview of the invention as defined in the appended claims.

What I claim as new and desire to secure by Letters Patent is:

1. The combination with a shoe sole cutting machine having an apron to receive a leather strip, a receiving wheel to receive the soles cut from said strip and an inclined vibrating trough to receive said soles from said wheel.

2. The combination with a shoe sole cutting machine having an apron to receive a leather strip, a receiving wheel having a plurality of spaced apart plates thereon to receive the soles cut from said strip, and a trough to receive said soles from said wheel.

3. The combination with a shoe sole cutting machine of a revolving receiving wheel having a plurality of spaced apart plates thereon adapted to receive the soles cut by said machine and an inclined trough adapted to receive said soles from said wheel, and means to vibrate said trough whereby said soles are caused to move on said trough.

4. The combination with a shoe sole cutting machine, of a revolving receiving wheel supported by said machine adapted to receive the soles cut by said machine, and an inclined vibrating trough adapted to receive said soles from said wheel, said trough adapted to convey said soles to a container.

5. The combination with a shoe sole cutting machine having an apron to receive a leather

strip from which the soles are cut by said machine, of a horizontal shaft mounted on said machine, means to intermittently rotate said shaft, a wheel having spaced apart blades 5 positioned below said apron, whereby said soles are adapted to be received between said blades from said apron, an inclined vibrating trough to receive said soles from said blades, whereby said soles are adapted to be automatically 10 conveyed to containers.

6. The combination with a shoe sole cutting machine having an apron to receive a leather strip from which the soles are cut by said machine, of a horizontal shaft mounted on said machine, means to rotate said shaft, a wheel having spaced apart blades positioned below said apron, whereby said soles are adapted to be received between said blades from said apron, an inclined vibrating trough to receive 15 said soles from said blades, whereby said soles are adapted to be automatically conveyed to containers.

7. A machine for cutting shoe soles and conveying said soles comprising a table, a cutting block on said table to receive said leather, a horizontal shaft rotatably mounted in the sides of said table, spaced apart wheels comprising hubs fixed to said shaft and having outwardly extending spaced apart plates 20 thereon, cutting knives, means to operate said knives toward and from said block to cut said soles from said leather, the outer edges of said plates being spaced from said block whereby manual movement of said leather toward said 25 wheels is adapted to permit the scrap material to fall through the space between said wheels and said block and said space being too narrow to permit the soles to fall there-through, said soles are forced over said space and between said plates, means to rotate said 30 wheels when said cutting knives are moving from said block to convey said soles outwardly of said machine, a support fixed to said machine, a trough inclined downwardly and outwardly of said machine, a trough inclined downwardly and outwardly of said machine and fixed to the upper end of said support and positioned under said wheels, whereby rotation of said wheels causes said soles to fall from said plates into said trough, and means to cause said trough to vibrate whereby said soles are caused to slide from said trough.

8. A machine for cutting shoe soles and conveying said soles comprising a table, a cutting block on said table to receive said leather, a horizontal shaft rotatably mounted in the sides of said table, spaced apart wheels comprising hubs fixed to said shaft and having outwardly extending spaced apart plates 45 thereon, cutting knives, means to operate said knives toward and from said block to cut said soles from said leather, the outer edges of said plates being spaced from said block whereby manual movement of said leather toward said 50 wheels is adapted to permit the scrap material to fall through the space between said wheels and said block and simultaneously force said soles over said space and between said plates, and means to rotate said wheel whereby said soles are moved outwardly of said machine.

9. A machine for cutting shoe soles and conveying said soles comprising a table, a cutting block on said table to receive said leather, a horizontal shaft rotatably mounted in the sides of said table, spaced apart wheels comprising hubs fixed to said shaft and having outwardly extending spaced apart plates 55 thereon, cutting knives, means to operate said knives toward and from said block to cut said soles from said leather, the outer edges of said plates being spaced from said block whereby manual movement of said leather toward said 60 wheels is adapted to permit the scrap material to fall through the space between said wheels and said block and simultaneously force said soles over said space and between said plates, and means to rotate said wheel whereby said soles are moved outwardly of said machine.

10. A machine for cutting and conveying shoe soles comprising a table, a cutting block on the top of said table to the portion of a strip of leather to be cut, spaced apart wheels rotatably mounted on said machine and having outwardly extending spaced apart plates, cutting knives, means to operate said knives toward and from said block to cut said soles from said leather positioned thereon, the outer edges of said plates of said wheels being spaced from said block whereby manual movement of said leather toward said wheels is adapted to permit the scrap material to fall through the space between said wheels and said block and simultaneously force said soles over said space and between said plates, and means to rotate said wheel whereby said soles are moved outwardly of said machine, a trough inclined downwardly and outwardly of said machine and positioned under said wheels, whereby rotation of said wheels causes said soles to fall from said plates into said trough, and means to cause said trough to vibrate whereby said soles are caused to slide from said trough.

11. A machine for cutting and conveying shoe soles comprising a table, a cutting block on the top of said table to the portion of a strip of leather to be cut, spaced apart wheels rotatably mounted on said machine and having outwardly extending spaced apart plates, cutting knives, means to operate said knives toward and from said block to cut said soles from said leather positioned thereon, the outer edges of said plates of said wheels being spaced from said block whereby manual movement of said leather toward said wheels is adapted to permit the scrap material to fall through the space between said wheels and said block and simultaneously force said soles over said space and between said plates, and means to rotate said wheel whereby said soles are moved outwardly of said machine, a support fixed to said machine, a trough inclined downwardly and outwardly of said machine and fixed to the upper end of said support and positioned under said wheels, whereby rotation of said wheels causes said soles to fall from said plates into said trough, and means to cause said trough to vibrate whereby said soles are caused to slide from said trough.

12. A machine for cutting and conveying shoe soles comprising a table, a cutting block on the top of said table to the portion of a strip of leather to be cut, spaced apart wheels rotatably mounted on said machine and having outwardly extending spaced apart plates, cutting knives, means to operate said knives toward and from said block to cut said soles from said leather positioned thereon, the outer edges of said plates of said wheels being spaced from said block whereby manual movement of said leather toward said wheels is adapted to permit the scrap material to fall through the space between said wheels and said block and simultaneously force said soles over said space and between said plates, and means to rotate said wheel whereby said soles are moved outwardly of said machine.

13. A machine of the class described comprising a table having sides and a top, a horizontal shaft rotatably mounted in the sides of said table, a wheel fixed to said shaft and having receiving partitions, cutting knives,

means to operate said knives toward and from said top to cut said soles from leather, the outer side of said wheel being spaced from an edge of said table whereby when said leather is manually moved on said top toward said wheel the scrap material is adapted to fall through the space between said wheel and said table and said soles are simultaneously forced over said space and into said partitions, means to rotate said wheel after said cutting knives have cut said soles whereby said soles are conveyed outwardly of said machine, a trough inclined downwardly and outwardly of said machine and fixed thereto, said trough being positioned under said wheel, whereby rotation of said wheel causes said soles to fall from said partitions into said trough, and means to cause said trough to vibrate whereby said soles are adapted to slide from said trough into containers positioned under said trough.

12. A machine of the class described comprising a table having sides and a top, a horizontal shaft rotatably mounted in the sides of said table, a wheel fixed to said shaft and having receiving partitions, cutting knives, means to operate said knives toward and from said top to cut said soles from leather, the outer side of said wheel being spaced from an edge of said table whereby when said leather is manually moved on said top toward said wheel the scrap material is adapted to fall through the space between said wheel and said table and said soles are simultaneously forced over said space and into said partitions, means to rotate said wheel whereby said soles are conveyed outwardly of said machine, a trough positioned under said wheel whereby rotation of said wheel causes said soles to fall from said partitions into said trough.

13. The combination with a shoe sole cutting machine adapted to cut left and right soles, of a pair of receiving wheels adapted to receive said left and right soles cut by said machine, a pair of chutes to receive said soles from said wheels and means whereby said chutes are positioned to receive said left and right soles respectively.

50 EDWIN W. TILTON.
